UNITED STATES PATENT OFFICE.

WILLIAM H. POUND, OF OSCEOLA, IOWA.

DESIGN FOR A GAME-BOARD.

SPECIFICATION forming part of Design No. 30,558, dated April 18, 1899.

Application filed December 19, 1898. Serial No. 699,773. Term of patent 31 years.

To all whom it may concern:

Be it known that I, WILLIAM H. POUND, a citizen of the United States, residing at Osceola, in the county of Clark, State of Iowa, 5 have invented and produced a new and original Design for Game-Boards, of which the following is a specification, reference being had to the accompanying drawings, forming a part thereof.

10 Figure 1 shows a top or plan view of the complete game-board. Fig. 2 shows a sectional view of the same.

Referring to the accompanying drawings, the leading or essential feature of the design 15 is a rectangular flat board, (indicated by the reference-numeral 10,) the surface of which is divided into squares of equal size by printing, there being eighteen squares on each side. Each alternate square is left plain, and these 20 squares are indicated by the numeral 11. Beginning at the bottom of the board, each of the lower tier of squares except the square 11 is printed extending in a pyramidal form from the base thus formed of the lower tier of 25 squares. All of the squares other than the square 11 are included in this pyramidal-shaped figure, the said squares being indicated by the numeral 12. On each of the squares above designated is fixed a block, 30 (indicated by the numeral 13.) Upon the surface of each block is the representation of a bee 14. On the top of the board each of the squares other than the square 11 is printed, and beginning from the top thus formed all 35 of those squares contained within an inverted

pyramidal configuration are printed, and indicated by the numeral 17. Upon the squares just mentioned is fixed a series of blocks, which are the exact counterparts or duplicates of the blocks hereinbefore described.

At the tier of the squares on the right edge of the board three central squares other than the squares 11 are printed, and indicated by the numeral 18, as are also the remaining squares contained within a figure of pyramidal shape, arranged with the said three black squares as a base, and upon the central one of said base-squares is fixed a block bearing the representation of a human head. This block is indicated by the numeral 19.

At the left side of the board is a pyramid of squares arranged in the same manner as the pyramid just described, said pyramid being indicated by the reference-numeral 20, and upon the central square of the base of the pyramid is fixed a block 21, having indicated thereon a human head.

All of the remaining squares other than the squares 11 are printed so as to be distinguishable from the squares 11, and are indicated by the reference-numeral 22.

The edge of the board is surrounded by three narrow strips 23, 24, and 25.

I claim as my invention—

The design for a game-board, substantially as herein shown and described.

WILLIAM H. POUND.
